UNITED STATES PATENT OFFICE.

EDWIN S. DAY AND HARRY B. HUBBARD, OF BELLINGHAM, WASHINGTON.

ATTACHMENT FOR LINOTYPE-MACHINES.

No. 821,342.

Specification of Letters Patent.

Patented May 22, 1906.

Application filed April 24, 1905. Serial No. 257,267.

To all whom it may concern:

Be it known that we, EDWIN S. DAY and HARRY B. HUBBARD, citizens of the United States of America, residing at Bellingham, in the county of Whatcom and State of Washington, have invented certain new and useful Improvements in Attachments for Linotype-Machines, of which the following is a specification.

This invention relates to new and useful improvements in linotype-machines, and more particularly in providing means for horizontally adjusting the transfer-fingers to suit the various measures or lengths of lines.

It is an object of this invention to provide novel means in a device of this kind wherein the adjusted parts are held against displacement.

It is also an object of the invention to provide for instantaneous adjustment to a fixed measurement.

Furthermore, an object of this invention is to produce a device of this character wherein absolute accuracy of measurement is obtained in the adjustment.

Finally, an object of this invention is to produce a device of the character noted that will be efficient and satisfactory in use and comparatively inexpensive to produce and maintain.

With the foregoing and other objects in view the invention consists in the details of construction and in the arrangement and combination of parts to be hereinafter more fully described and claimed.

In describing the invention in detail reference will be had to the accompanying drawings, forming part of this specification, wherein like characters denote corresponding parts in the several views, in which—

Figure 1 represents in front elevation the assembling mechanism of a linotype-machine with the invention applied thereto. Fig. 2 is a top plan view of the carriage. Fig. 3 is a side elevation of Fig. 2. Fig. 4 is a sectional view illustrating details of the invention.

In the drawings, Fig. 1 illustrates the well-known form of linotype-machine as disclosed in Patent No. 726,019, and in view of the dis-

closure therein no detail will be given in this specification except that which is pertinent to the invention at hand.

In the drawings, 1 indicates the carriage suitably mounted on the main frame 2, and is provided with two depending fingers 3 4, having a normal separation slightly greater than that of the composed line for the purpose readily understood. Formed on the carriage 1 near each end are lugs 5 6, in which is suitably mounted a horizontal rod 7. This rod is provided with a flattened face 8, which has a series of transverse slots or grooves 9, arranged in pica measure. To the lug 6 the finger 4 is rigidly connected, while the finger 3 is mounted on the rod 7 and is intended to slide thereon to attain the different adjustments desired. The portion of the finger 3 embracing the rod 7 is provided with a hollow boss 10, through which passes a rod or bolt 12. The inner end of this rod has a head 11, which has its face flat, but centrally of the face and extending entirely thereacross is a lug 13, at right angles thereto, adapted to fit snugly within the grooves 9 of the rod 7. This projection normally engages the wall of a groove 9 at all times, and to hold it in its normal position a spiral spring 14 is caused to embrace the bolt 12 and bear against the head 11 and an annular shoulder 16 within the bore of the boss. To the outer end of the bolt 12 is attached a button or thumb-piece 17, by means of which the bolt 12 is raised from within the groove 9.

The construction and operation of the device are thought to be clearly apparent from the foregoing, attention being directed to the fact that the pica measurement assures a quick and accurate adjustment, while the contact of the head with the grooves assures a permanent adjustment.

Having fully described our invention, what we claim as new, and desire to secure by Letters Patent, is—

In a linotype-machine, a carriage, a rod carried thereby, having transverse grooves, a finger on the carriage, a finger slidable on the rod, said finger having a hollow boss on the end embracing the rod, said boss being provided with an annular shoulder within the

bore, a bolt slidable in the boss, a head on the bolt engaging the transverse grooves, a spring embracing the bolt and bearing against the head and the shoulder of the bore, and a finger-piece on the bolt, substantially as described.

In testimony whereof we affix our signa-

tures, in the presence of two witnesses, this 12th day of April, 1905.

EDWIN S. DAY.

HARRY B. HUBBARD
